UNITED STATES PATENT OFFICE.

NANCY ELLA BURCH, OF CARTHAGE, MISSOURI.

FLOWER-STAND.

SPECIFICATION forming part of Letters Patent No. 324,079, dated August 11, 1885.

Application filed December 13, 1884. (Model.)

To all whom it may concern:

Be it known that I, NANCY ELLA BURCH, of Carthage, in the county of Jasper and State of Missouri, have invented a new and Improved 5 Flower-Stand, of which the following is a full, clear, and exact description.

The object of my invention is to provide a new and improved flower-stand for holding flowers in pots, and so that the flowers can be 10 watered without wetting or soiling the floor.

The invention consists in the peculiar construction and arrangement of parts, as herein-after fully described, and pointed out in the claims.

15 Reference is to be had to the accompanying drawings, forming part of this specification, in which similar letters of reference indicate corresponding parts in both the figures.

Figure 1 is a side view of my improved 20 flower-stand, parts being broken out and others being in section. Fig. 2 is a plan view of the same, parts being broken out.

The standard A, which may have legs of any desired suitable kind, is provided in its 25 top with a funnel-shaped or semi-spherical cavity, B, for receiving a metal or other funnel, C, from which a tube, D, projects downward to the top of a cavity or recess, E, formed in the standard below the funnel, and adapted

30 to receive a vessel, F, provided with a neck, G, on which an internally-screw-threaded coupling-sleeve, H, is held to turn, the said neck being adapted to be screwed on the externally-screw-threaded lower end of the con- 35 ducting-tube D. Cross-pieces J are secured on the top of the standard and extend over the funnel, and from the middles or intersection of the said cross-pieces a pin or pivot, K, projects upward and through the middles or 40 intersection of cross-pieces L on a hollow circular top, M, provided with an annular track, N, which rests upon rollers O, pivoted in jaws projecting upward from the top of the stand- 45 ard. An annular trough, P, is secured on the projecting ends of the cross-pieces J, outside of and concentric with the annular top of the standard, and gutters Q extend from the annular trough P into the upper part of the funnel C. The revolving top M is provided with 50 three or more or less risers or offsets, R, pro- 55 vided with a series of holes, S, for receiving the flower-pots, which rest upon apertured

plates T, secured to the under sides of the horizontal steps. Slots or other openings, V, are formed in the risers or vertical parts of the 55 steps to permit air to circulate under the pots. The standard is provided with casters or rollers. The drip-water from the pots on the inner two steps or offsets drops directly into the funnel C, and the water from the pots on the 60 outer step drops into the gutter P, and then flows through the gutters Q into the funnel and from the same into the vessel F, which is preferably made of glass, so that the level of the water in the same can be seen. When the 65 vessel F is filled, the coupling H is unscrewed and the vessel removed. The flowers in the pots can be watered without soiling or wetting the floor, and the top can easily be turned and each pot reached.

I do not limit myself to the exact details of construction as shown and described—as, for instance, if desired, the funnel C can be made shallow and cone-shaped instead of semi-spherical. Such a funnel can be more readily made and will occupy less space in the stand.

Having thus fully described my invention, I claim as new and desire to secure by Letters Patent—

1. In a flower-stand, the combination, with 80 a standard, of a funnel in the body of the same, and a revolving top having steps or offsets above the funnel and communicating with the said funnel, substantially as herein shown and described.

2. In a flower-stand, the combination, with 85 the standard A and the funnel C in the body of the same, of the revolving top M and the rollers O, journaled in supports in the said standard, substantially as herein shown and 90 described.

3. In a flower-stand, the combination, with 95 the standard A and the funnel C, of the cross-pieces J, the annular outer gutter, P, on the ends of the same, the radial gutters Q, and the revolving top M, substantially as herein shown and described.

4. In a flower-stand, the combination, with 100 the standard A, having the recess E, of the funnel C, the tube D, the vessel F in the recess E, the coupling H, and the flower-pot-supporting top M on the top of the standard and communicating with said funnel, substantially as herein shown and described,

5. In a flower-stand, the combination, with the standard A and funnel C, of the top M, having holes S, and of the apertured plates T below the holes S, substantially as herein shown and described.

6. In a flower-stand, the combination, with the standard A, having funnel C, and provided with the rollers O, of the flower-supporting

top M, pivoted above the standard and having the track N, substantially as shown and so described.

NANCY ELLA BURCH.
